Primary Examiner — Phillip S Hyder*(74) Attorney, Agent, or Firm* — Venable LLP; Steven J. Schwarz; Laura G. Remus(57) CLAIM

The ornamental design for a cosmetic brush, as shown and described.

DESCRIPTION

FIG. 1 is a top perspective view of a cosmetic brush showing my new design.

FIG. 2 is a top view of a cosmetic brush showing my new design; and,

FIG. 3 is a first side view of a cosmetic brush showing my new design.

The ornamental design which is claimed is shown in solid lines in the drawings. The broken lines in the drawings are for illustrative purposes only and form no part of the claimed design.

1 Claim, 3 Drawing SheetsMatter enclosed in heavy brackets [ ] appears in the original patent but forms no part of this reissue; matter printed in italics indicates the additions made by reissue.| (56) References Cited		JP	2007 319211 A	12/2007

INVENTOR(S) : Waitesmith

It is certified that error appears in the above-identified patent and that said Letters Patent is hereby corrected as shown below:

In the Specification

Under the heading "DESCRIPTION," before the first line, i.e., "FIG. 1 is a top perspective view of a cosmetic brush showing," please insert the paragraph, as follows:

--NOTICE: More than one reissue application has been filed for the reissue of U.S. Patent No. D699,041 S. The reissue applications are U.S. Reissue Patent Application Serial Nos. 29/650,936 and 29/650,930, each filed on June 11, 2018, now U.S. Reissue Patent No. RE47,359 E and RE47,847 E, respectively, issued April 23, 2019 and February 11, 2020, respectively, which are a continuation reissue application and a divisional reissue application, respectively, of U.S. Reissue Patent Application Serial No. 29/554,344 (the present application), filed on February 10, 2016, now U.S. Reissue Patent No. RE46,939 E, issued July 10, 2018, which is a reissue application of U.S. Design Patent Application Serial No. 29/425,384, filed on June 22, 2012, now U.S. Design Patent No. D699,041 S, issued February 11, 2014, which is a continuation of U.S. Patent Application Serial No. 12/425,182, filed April 16, 2009, now abandoned.--
